UNITED STATES PATENT OFFICE

HENRY D'OLIER, JR., OF BRIDGEPORT, CONNECTICUT

LIGHTING FIXTURE

Application filed June 24, 1927. Serial No. 201,236.

My invention relates to lighting fixtures and more particularly to an assembly of parts commonly known as a lighting globe, a reflector and a holder.

5 One of the objects of my invention is to provide a holder and reflector adapted to embrace the neck of a lighting globe in such a manner as to cause the globe to support the reflector, the globe in turn being supported 10 by the holder.

The invention will be readily understood from the following specification together with the accompanying drawings in which like references refer to similar elements in 15 the respective figures.

Figure 1 is a sectional, schematic view of one form of my invention assembled.

Figure 2 is an enlarged section of the globe neck reflector and holder shown in Figure 1 20 wherein the respective parts are about to be brought together in operative relationship.

Figure 3 shows the elements of Figure 2 in operative relationship.

Figure 4 shows a modified form of holder.

25 Figure 5 shows a modified form of securing the parts of Figure 4 in operative relationship.

Figure 6 is a sectional view along the line 6—6 of Figure 5.

30 Referring particularly to Figure 1, 1 is a lighting globe having a neck portion as at 2 about the outside of which neck an annular channel 3 is formed.

4 is a shade having an opening 5 adapted 35 to receive the neck portion of the globe.

An annular flange 6 is provided about the opening 5 in the shade over which a bead 7 on holder 8 is adapted to fit when the parts are brought into operative relation.

40 Screws 9 are adapted to project through threaded openings 10 and holder 8 and engage with the neck 2 of globe 1 to secure the assembly in operative relation.

The reflector is adapted to rest adjacent 45 with the opening 5 upon the globe 1 as at 11.

The assembly and operation is as follows:—

Reflector 4 has projected through the neck portion 2 of globe 1 and rests upon the globe 50 as at 11. The holder 8 is brought down over

the neck 2 of globe 1 projecting through the opening in the reflector. Screws 9 are inserted in threaded openings 10 and holder and projected therethrough until they engage with the upper portion of annular ring about 55 the neck of the globe. It will be readily noted that as screws 9 are turned up, they will draw the holder 8 down towards the reflector 4 and cause the bead 7 on the holder to embrace or slip over flange 6 of the reflector and as the 60 screws 9 are projected further into the annular ring 3, the relative telescopic movement between holder 8 and the neck of globe 1 continues until screws 9 have found the deepest part of annular ring or channel 3 or until the 65 holder 8 is brought snugly and securely down on the reflector pressing the latter against the globe 1. Of course it is obvious that the relation of the parts will be such that reflector 70 4 will be fitted on globe 1, flange 6 of the reflector being embraced by bead 7 on holder 8 before the screws 9 find the deepest part of the annular channel 3.

Referring to Figure 2, it will be noted that screw 9 is engaging with the upper portion 75 of annular channel 3 about the neck of the globe 1 and that bead 7 of holder 8 has not yet engaged with or embraced flange 6 of reflector 4 whereas in Figure 3 the full line position of the respective elements shows the 80 parts in operative position.

In Figure 4 holder 8 is shown without bead 85 7 being merely enlarged in inside diameter sufficiently to overlap or embrace bead 6 by a straight section in the holder 8.

It will be fully obvious to those skilled in the art that other means than threaded means 9 may be used to engage the neck of holder 1 to secure the parts in operative relationship and as shown in Figures 5 and 6 an opening 12 90 in holder 8 through which a spring clip 13 is provided in which the operation consists of pulling the spring clip 13 outwardly through opening 12 in holder 8 as indicated at 13—A in Figure 6 as the holder is brought down over the neck 2 of the globe. Clips 13 are 95 then released and as they seek to find their normal position as shown in the full lines of Figures 5 and 6, they engage with the upper portion of the channel 3 about the neck of the 100

globe and force the parts together and secure them in operative relationship.

It will be noted that a minimum number of parts are necessary in this novel structure and 5 that screws 9 or clips 13 do not project through or engage with reflector 4 at all.

Other modifications of parts embodying my invention will be readily apparent to those skilled in the art and I claim as my invention 10 all such modifications as follows within the scope of the following claims:—

What I claim is:

1. In a lighting fixture, a globe having a neck provided with a channel, the latter having 15 a downwardly and inwardly inclined wall, a reflector having an opening therein to receive the neck and being engaged with the globe and provided with a annular upwardly extending flange, a holder formed to engage about the neck and having its lower portion formed to engage with the flange of the reflector and with the top of the latter so as to hold the reflector against the globe, and screws disposed spaced above the flange 20 of the reflector and extending through the lower portion of the holder and engageable with said inclined wall of the channel whereby upon inward turning of the screws same will ride downwardly on said wall and thereby cause the holder to engage the flange of the reflector to center the latter and simultaneously force the reflector against the globe.

2. In a lighting fixture, a globe having a neck provided with a channel, the latter having 30 a downwardly and inwardly inclined wall, a reflector having an opening therein to receive the neck and being engaged with the globe and provided with an annular upwardly extending flange, a holder formed to engage about the neck and provided with a curved flange at its lower part, the free edge of which curved flange engages with the flange of the reflector and with the top of the latter so as to hold 35 the reflector against the globe, and screws disposed above the flange of the reflector and extending through the lower portion of the holder and engageable with said inclined wall of the channel whereby upon inward turning 40 of the screws same will ride downwardly on said wall and thereby cause the curved flange of the holder to engage the flange of the reflector and center the latter and simultaneously force the reflector against the globe.

3. In a lighting fixture, a globe having a neck provided with a channel the latter having 50 a downwardly and inwardly inclined wall, a reflector having an opening therein to receive the neck and being engaged with the globe and provided with an annular upwardly extending flange, a holder formed to engage about the neck and having its lower portion formed to engage with the flange of 55 the reflector and with the top of the latter

so as to hold the reflector against the globe, and means carried by the holder and disposed above the flange of the reflector and engageable with said inclined wall of the channel 70 so as to ride downwardly thereon and cause the holder to engage the flange of the reflector to center the latter and to simultaneously force the reflector against the top of the globe.

4. In a lighting fixture, a globe having a neck provided with a channel, the latter having a downwardly and inwardly inclined wall, a reflector having an opening therein to receive the neck and being engaged with the globe and provided with an annular upwardly extending flange, a holder formed to engage about the neck and provided with a curved flange at its lower part the free edge of which curved flange is adapted to engage 80 the flange of the reflector and the top of the latter so as to hold the reflector against the globe, and means carried by the holder and disposed above the flange of the reflector and engageable with said inclined wall of the channel 85 so as to ride downwardly thereon and cause the curved flange of the holder to engage the flange of the reflector to center the latter and to simultaneously force the reflector against the top of the globe.

In testimony whereof I affix my signature.
